UNITED STATES PATENT OFFICE.

HOWARD E. BURNS, OF CHICAGO, ILLINOIS, ASSIGNOR TO THE C. F. MASSEY COMPANY,
OF CHICAGO, ILLINOIS, A CORPORATION OF ILLINOIS.

DESIGN FOR A CONCRETE SMOKE-JACK.

50,903.

Specification for Design.

Patented June 12, 1917.

Application filed March 30, 1917. Serial No. 158,752. Term of patent 14 years.

To all whom it may concern:

Be it known that I, HOWARD E. BURNS, a citizen of the United States, residing in Chicago, in the county of Cook and State of Illinois, have invented a new, original, and ornamental Design for Concrete Smoke-Jacks, of which the following is a specification, reference being had to the accompanying drawing, forming a part thereof.

In the drawing Figure 1 is a side eleva-

tional view and Fig. 2 an end elevational view of a concrete smoke jack showing my new design.

I claim:

The ornamental design for concrete smoke jack as shown.

HOWARD E. BURNS.
